FOOD BALL MOLD

John W. Bentley, San Pablo, Calif.

Application February 19, 1959, Serial No. 54,684

Term of patent 14 years

(Cl. D44—4)

FIG. 1

FIG. 2

Figure 1 is a side elevational view of a food ball mold showing my new design; and

Figure 2 is a plan view thereof.

I claim:

The ornamental design for a food ball mold, substantially as shown.
